UNITED STATES PATENT OFFICE.

JAMES S. COPELAND, OF HARTFORD, CONNECTICUT.

DESIGN FOR A GEAR-CASE.

SPECIFICATION forming part of Design No. 28,432, dated March 29, 1898.

Application filed August 3, 1897. Serial No. 646,979. Term of patent 14 years.

To all whom it may concern:

Be it known that I, JAMES S. COPELAND, a citizen of the United States, and a resident of Hartford, in the county of Hartford and State of Connecticut, have invented a new and original Design for Gear-Cases; and I do hereby declare the following, when taken in connection with the accompanying drawings and letters of reference marked thereon, to be a full, clear, and exact description of the same, and said drawings constitute part of this specification, and represent, in—

Figure 1, a top view of a gear-case embodying my design, and in Fig. 2 a view in side elevation of the gear-case.

My design consists of a bulbous structure *a*, united near one side to a similar bulbous body *c*, located at an angle with the first, said angle being, as shown in the drawings, about ninety degrees. One of said bulbous parts *a* is provided with a reduced portion *b* on the

surface facing outward from that side on which the two bulbous structures are united.

The bulbous body *c* is provided with rounded edges *d e* when seen in plan view, as in Fig. 1, this body *c* when seen in side view, as in Fig. 2, having a circular form.

The characteristic or leading feature of my design consists of the two bulbous bodies united near one side and placed at an angle 30 each with the other.

I claim—

The design for a gear-case substantially as shown.

In testimony whereof I have signed this 35 specification in the presence of two subscribing witnesses.

JAMES S. COPELAND.
